(57) **CLAIM**

The ornamental design for the audio video display device with user interface, as shown and described.

DESCRIPTION

FIG. 1 is a plan view of a first embodiment of the audio video display device with user interface;

FIG. 2 is a plan view of a second embodiment of the audio video display device with user interface;

FIG. 3 is a plan view of a third embodiment of the audio video display device with user interface;

FIG. 4 is a plan view of a fourth embodiment of the audio video display device with user interface; and,

FIG. 5 is a plan view of a fifth embodiment of the audio video display device with user interface.

The square that is shown surrounding the content of the drawings is the display device.
